UNITED STATES PATENT OFFICE

95,898

DESIGN FOR A SPOON OR OTHER ARTICLE OF FLATWARE

Virginia M. Conner, New York, N. Y.

Application March 20, 1935, Serial No. 55,964

Term of patent 3½ years

To all whom it may concern:

Be it known that I, Virginia M. Conner, a citizen of the United States, residing at New York, in the county and State of New York, have invented a new, original, and ornamental Design for a Spoon or Other Article of Flatware, of which the following is a specification, reference being had to the accompanying drawing, forming part thereof, wherein

Fig. 2 is a cross section of the device shown in Fig. 1 taken along the line 2—2; and
Fig. 3 is a side view of the device shown in Fig. 1.

In each figure the dominant features of the design have been shown in full lines.

I claim:

The ornamental design for a spoon or other article of flatware substantially as shown and described.

VIRGINIA M. CONNER.
